COMBINED PEDAL AND STIRRUP OR SIMILAR ARTICLE

Richard J. Harwood, Wichita, Kans., assignor to
Exer-matic, Inc., Wichita, Kans.

Filed Aug. 1, 1960, Ser. No. 61,579

Term of patent 14 years

(Cl. D90—19)

FIG. 1

FIG. 2

FIG. 3

FIG. 4

FIG. 5

FIG. 6

FIG. 1 is a side elevational view of a combined pedal and stirrup showing my new design.

FIG. 2 is a front elevational view of same.

FIG. 3 is an elevational view of the other side of said combined pedal and stirrup.

FIG. 4 is a rear elevational view of said combined pedal and stirrup.

FIG. 5 is a top plan view of said combined pedal and stirrup.

FIG. 6 is a bottom plan view of said combined pedal and stirrup.

The dominant features of my design reside in the full-line portions of the drawing.

I claim:

The ornamental design for a combined pedal and stirrup or similar article, as shown and described.
